C. L. Paulus

By Robert H. Young Attorney

UNITED STATES PATENT OFFICE.

CHARLES LEIGH PAULUS, OF DAYTON, OHIO.

TRIGGER MECHANISM FOR DUPLEX FLEXIBLE GUNS.

Application filed March 9, 1922. Serial No. 542,334.

To all whom it may concern:

Be it known that I, CHARLES LEIGH PAULUS, a citizen of the United States, residing at Dayton, in the county of Montgomery and State of Ohio, have invented certain new and useful Improvements in Trigger Mechanism for Duplex Flexible Guns, of which the following is a specification.

10 My invention relates to the trigger mechanism of flexibly mounted machine guns such as are used on aircraft.

The object of my invention is to provide an auxiliary trigger mechanism which may 15 be mounted on the hand grip of one gun to enable the gunner to operate or fire two guns without moving his hand from said hand grip. The auxiliary trigger mechanism may be mounted on either gun and 20 the guns may be fired concurrently or successively.

The invention consists in the novel construction, combination and arrangement herein fully described, illustrated and 25 claimed.

In the accompanying drawings:

Fig. 1 is a vertical section of the auxiliary trigger mechanism in its applied relation to the hand grip of a machine gun;

30 Fig. 2 is a section on the line 2—2 of Fig. 1; and

Fig. 3 is a rear elevation of the auxiliary trigger mechanism, detached.

In the drawings 5 represents the spade 35 handle of a flexibly mounted machine gun and 6 the hand grip forming a part thereof. The spade handle is shown as having a trigger guard 7 for the trigger of said gun.

To enable a second gun to be fired by the 40 gunner without removing his hand from the grip 6, I employ an auxiliary trigger mechanism embodying a mounting plate 8 designed to fit against the forward face of the grip 6, as shown, and preferably having 45 spurs 9 which positively engage said grip and prevent slippage of the mounting plate on the grip when tightly clamped against the latter.

The mounting plate 8 is secured to the 50 grip 6 by a clamp 10 in the form of a band

which passes around the grip. A clamping bolt 11 passes through the end portions 12 of the band 10 and serves also as a pivot for an auxiliary trigger 13. The plate 8 has a stop arm 14 against which the trigger 13 normally rests as shown in Fig 1, and also has a slot 15 to receive the pivot knuckle 16 of the trigger.

The trigger 13 has a hole 17 therein to receive a flexible connection 18, such as a 60 Bowden wire control, to lead to the trigger of the other gun, the connection 18 working in a flexible tubular casing 19 connecting the two guns.

The gunner places his hand on the grip 6, with his index finger above the guard 7 against the trigger of that gun, and his second finger against the trigger 13 of the auxiliary trigger mechanism. He may then pull either of the triggers, one at a time or 70 both simultaneously. This is advantageous for the reason that with a flexible gun mount such as is now used on aircraft, the gunner must use one hand to operate the Scarf ring while his other hand is grasping the spade 75 grip of the gun carrying the auxiliary trigger mechanism in addition to its own trigger mechanism.

I claim:

1. In combination with the spade grip of 80 a flexibly mounted gun, an auxiliary trigger mechanism for firing another gun, said mechanism embodying a mounting plate, a quickly detachable clamp to secure said plate to the spade grip, a trigger mounted on said 85 plate, and a flexible connection leading from said trigger to the trigger of the other gun.

2. In combination with the hand grip of a 90 flexibly mounted gun, an auxiliary trigger mechanism for firing another gun, said mechanism embodying a mounting plate, a clamp to secure said plate to the front of the hand grip, a trigger mounted on said plate, a bolt 95 acting to tighten said clamp upon the hand grip, and also forming the pivot of said trigger, and a flexible connection leading from said trigger to the trigger of the other gun.

In testimony whereof I affix my signature.

CHARLES LEIGH PAULUS.
